2,103,107

CONTAINER CONVEYER AND DISTRIBUTOR

Christian N. Bergmann, Pittsburgh, Pa., assignor
of two-sixths to Charles M. Clarke, Sewickley,
Pa.

Application September 11, 1936, Serial No. 100,304

11 Claims. (Cl. 198—81)

My invention is an improvement in distributing conveyers for containers, such as bottles, cans, or the like, and is particularly adapted to the art of conveying milk or other bottles, as from a washing machine, to a plurality of receiving stations for further treatment.

Specifically, in the application of the invention as illustrated and as hereinafter described, the invention involves the installation of a main sectional conveyer or trackway and one or more divisional lateral trackways, and an automatically operating switching construction at their junction for dividing or subdividing a main stream or series of bottles into plural streams.

The invention has in view provision of means whereby a constant stream or train of bottles may be conveyed and delivered to the ultimate one of a series of terminal receiving stations, and to one or more intermediate laterally disposed stations automatically, as controlled or limited by the absorbing or receiving capacity of the several stations, or their supply conveyers.

While the invention as herein disclosed refers to the art or practice of washing and filling milk bottles, it will be understood that it may be utilized in connection with a main quantity of similar containers or other generally similar objects capable of being progressed, while standing upright, by a supporting conveyer, as a belt or chain, for distribution.

The principal active features or elements of the invention consist in interposing between the terminals of sections of a main conveyer, the receiving terminals of laterally arranged conveyers adapted to deflect units from the main stream to one or more intermediate stations. Also in providing bridging and guiding elements whereby under varying operating conditions the units may pass from the main trackway onto a lateral one, or may pass over an interposed lateral trackway to the opposite terminal of the main one.

The invention is also designed to maintain the feed of units to one or more receiving stations in proportion to the absorbing or receiving capacity of each.

Referring to the drawings showing certain preferred constructions and arrangement:

Fig. 1 is a diagrammatic plan view illustrating the invention as utilized for alternating single bottle straight travel movement and intermediate lateral and final disposition;

Fig. 2 is a similar diagrammatic sectional view on the line II—II of Fig. 1;

Fig. 3 is a diagrammatic plan view of the sec-

tional conveyer chain and gearing arrangement thereof;

Fig. 4 is a diagrammatic plan view showing the elemental conveyer arrangement at a switching junction;

Fig. 5 is a similar sectional view on the line V—V of Fig. 4;

Fig. 6 is a detail plan view of a switching junction cover plate embodying the transfer bridge sections.

Ordinarily, the present practice is to convey bottles from a washer to each filling machine by separate independent conveyers. In my invention I accomplish the results by the distributing system hereinafter described.

Fig. 1 illustrates one of several possible adaptations of the invention to the solution of the problem of distributing the normal output of a single washing machine to a plurality of subsequent stations and operations, as in filling the bottles.

Ordinarily the capacity output of a single washing machine is greatly in excess of that of a single filling machine, hence it is desirable and necessary to apportion the supply or rate of feed of bottles to a plurality of filling machines proportionally.

In the layout of Fig. 1 the washing machine A, with a capacity and output of say 240 per minute, supplies its bottles to filling machine B having a large capacity of say 120 per minute; to machine C having a reduced capacity of say 60 per minute; and to machine D having a similar reduced capacity of say 60 per minute.

The invention however is not limited to any fixed proportions or capacities, and may be varied within wide limits, dependent on conditions.

The washing machine A discharges its output in successive rows of say 12 bottles each, bottoms down, onto a sectional conveyer trackway 5, 5a, and 5b. The trackway is of conventional form, having a lower supporting and conveying belt or chain 6 of suitable construction, flexible vertically, as commonly practiced, and driven by any suitable means, as motor M.

The speed of conveyer section 5 is adjusted to the discharge speed of the washing machine so that each row of bottles as discharged will be located just behind the preceding advancing row in transit.

However it is desirable that the speed of the conveyer shall be sufficient to compensate for any gap spaces between the bottles and to maintain them in close pushing contact with each other until or as they arrive successively at the first

switching station E, and also the second station F.

At such first station E it is desirable to divide the advancing column so as to divert a portion laterally, transferring such portion to filling machine B according to its capacity, and the balance along the main sectional trackway 5a. I therefore provide a lateral conveyer-provided trackway 7 leading from station E to the filling machine 10 B, along which trackway some of the bottles of the main column are carried, the others proceeding straight along trackway 5a.

In the same manner other bottles of the main series pass beyond station E by trackway conveyer 5a to the second switching station F, and by lateral trackway 8 to filling machine C, the remaining bottles then passing along trackway conveyer 5b directly or by lateral trackway 9 to the final filling machine D.

20 The construction of the several conveyers is of any well known type to provide progressive movement on a common level, of closely adjacent unit supporting and carrying slats 10.

25 The conveyers are driven by suitable actuating mechanism at desired speeds for movement of the units, and the speeds may be regulated to accommodate the receiving capacity of the several filling machines B, C, and D.

Thus the speed of conveyer section or trackway 30 5 is the same or slightly slower than that of the preliminary conveyer leading to it from the washer A. The next section 5a is preferably of reduced speed, as is also the final section 5b and the speeds of lateral conveyers 7, 8, and 9 are 35 conformably regulated to the receiving capacity of the filling machines. Such details and adjustments will be understood as within the province of the builder or designing engineer, dependent upon the operating conditions of the installation 40 or other controlling factors.

At each station E and F, or wherever a lateral conveyer leads off between the terminals of the consecutively spaced sections of a main conveyer, I provide a comparatively thin flat supporting 45 bridge section 12, forming a portion of a covering plate 13.

Such plate as in Fig. 6 is provided with clearance openings 14 for the adjacent terminal portions of the main conveyer sections 5 and 5a and 50 5b, and with a middle clearance portion 15 for the chains and slats of lateral conveyers 7 and 8.

The plate 13 as thus made is adapted to be laid across the gap portions at station E and F and is preferably on a level slightly below that of the 55 supporting slats 10, providing an ample supporting platform for the straight or lateral movement of the units.

By such construction, assuming all the conveyer sections to be loaded, as the bottle units are 60 advanced, say along conveyer trackway 5, they will ride over the bridge section 12 onto the lateral conveyer 7, by which they will be conveyed to machine B. Assuming conveyer 7 to have been loaded to its delivering capacity, or temporarily interrupted, the progressing series of 65 units will be pushed continuously along over the lateral conveyer and the opposite bridge section 12 and be conveyed by section 5a to lateral conveyer 8 under the same conditions. It will be 70 understood that the receiving capacity of machines B and C combined is less than the feeding capacity from the washer, and that all bottles not distributed laterally will thus pass onwardly through the final conveyer trackway 5b and 9 to 75 the remaining machine D.

Each lateral conveyer 7 and 8, preferably travelling at a slower speed than either of the main sections 5 or 5a will of course only receive and carry off such maximum of bottles delivered thereto as limited by the capacity of machines 5 B and C. Each last bottle passing onto the lateral conveyer will thus leave an open gap for straight line progress of the remaining surplus of the main column.

It will also be understood in case of, for instance, machine D being temporarily inoperative, that the entrance to conveyer section 5b may be blocked off in any suitable manner, whereupon units arriving at the station junction F will all be carried to machine C. Also, that if either 15 machine B or C is temporarily inoperative, entrance to either conveyer 7 or 8 may be closed in the same manner with resulting longitudinal progress along the main section or sections.

The several trackways are defined by the travelling base slat members 10 and between the guiding sides 11, 11, of suitable construction to maintain the bottles erect, with easy clearance in their passage. At corner portions such sides may be conformably rounded to provide for easy lateral travel of the units as delivered from one line of direction to another, as is commonly practiced in similar conveying mechanism. Also at station E and F the approaching or inlet end of lateral conveyers 7 and 8 is receivably widened by sloping 30 or rounding the inner guiding side 11a, providing for easy lateral movement of the units, as deflected thereinto by cooperation of the associated conveyer elements, and as controlled by the preceding units.

What I claim is:

1. In combination with a plurality of spaced apart sections of a longitudinal conveyer trackway on a common horizontal plane, a lateral conveyer on the same plane extending transversely between their terminals in receiving position relation to one of said trackways, said conveyer and trackways being of the flexibly connected supporting flight type.

2. In combination with a plurality of spaced apart sections of a longitudinal conveyer trackway on a common horizontal plane, a lateral conveyer on the same plane extending transversely between their terminals in laterally receiving and conveying relation to one of said trackways, 50 said conveyer and trackways being of the flexibly connected supporting flight type.

3. In combination, a pair of spaced apart longitudinal conveyers in registering alinement on a common horizontal plane whereby one delivers 55 to the other, and an intervening transverse conveyer on the same plane adapted to receive units from an approaching conveyer member thereof.

4. In combination, a pair of spaced apart longitudinal conveyers in registering alinement on a common horizontal plane whereby one delivers to the other, an intervening transverse conveyer on the same plane adapted to receive units from an approaching conveyer member thereof, and stationary bridge sections between 60 the terminals of the longitudinal conveyers and the transverse conveyer.

5. In combination, a plurality of conveyer sections in longitudinal alinement on a common horizontal plane providing adjacent delivering 70 and receiving terminals at each side of an intervening transverse space, a lateral conveyer trackway in said space disposed across the path of said sections and on the same plane, and bridging members between the longitudinal and transverse 75

sections, said conveyer and trackways being of the flexibly connected supporting flight type.

6. In combination, a plurality of conveyer sections in longitudinal horizontal alignment providing adjacent delivering and receiving terminals at each side of an intervening transverse space, a lateral conveyer trackway in said space disposed across the path of said sections, and bridging members between the longitudinal and transverse sections substantially in the plane of both trackways, said conveyer and trackways being of the flexibly connected supporting flight type.

7. In combination, a plurality of conveyer trackway sections in longitudinal alignment providing adjacent delivering and receiving terminals at each side of an intervening transverse space, a lateral conveyer trackway in said space disposed across the path of said sections, means for moving the several conveyer trackway sections at successively reduced speeds, and bridging members between the longitudinal and transverse conveyer trackway sections.

8. In a unit distributing conveyer system, the combination of an initial unit supply station, a plurality of conveyer sections in longitudinal alignment providing adjacent delivering and receiving terminals at each side of an intervening transverse space, a laterally arranged receiving station, a lateral conveyer trackway in said space disposed across the path of said sections and leading to said receiving station, and bridging members between the longitudinal and transverse sections, said conveyer and trackways being of the flexibly connected supporting flight type.

9. In a unit distributing conveyer system, the combination of an initial unit supply station, a plurality of conveyer sections in longitudinal alignment providing adjacent delivering and receiving terminals at each side of an intervening transverse space, a laterally arranged receiving station, a terminal station in receiving relation to the furthermost longitudinal section, a lateral conveyer trackway disposed in the space between the terminals and across the path of the longitudinal sections and leading to said receiving station, and bridging members between the longitudinal and transverse sections, said conveyer and trackways being of the flexibly connected supporting flight type.

10. In combination with the delivering and receiving terminals of a pair of spaced apart longitudinal conveyers and the receiving terminal of an intervening lateral conveyer, a bridge member having a supporting surface substantially on the plane of all of said conveyers having oppositely located clearance openings for the terminals of the longitudinal conveyers and a clearance opening for the terminal of the lateral conveyer extending between said openings.

11. A bridge member for horizontal longitudinal and lateral conveyers having a plane upper surface and oppositely located clearance openings for the terminals of the longitudinal conveyers and a clearance opening for the terminal of the lateral conveyer extending between said openings.
